UNITED STATES PATENT OFFICE.

CHRISTOPHER CHARLES LINDENBERG, OF READING, MASSACHUSETTS.

THEATER-SEAT CONSTRUCTION.

1,259,754.

Specification of Letters Patent. Patented Mar. 19, 1918.

Application filed May 2, 1917. Serial No. 165,940.

To all whom it may concern:

Be it known that I, CHRISTOPHER CHARLES LINDENBERG, a subject of the Czar of Russia, residing at Reading, in the county of 5 Middlesex and State of Massachusetts, have invented new and useful Improvements in Theater-Seat Constructions, of which the following is a specification.

This invention relates to seat construction 10 and especially to seats of chairs adapted for use in theaters or other public places.

The primary object of the invention is to utilize the space beneath the seat for the purpose of providing a casing or closet in 15 which the wraps of occupants of the seat may be placed in a manner to protect the same, the said casing being vertically disposed and of sufficient depth to permit of a coat or wrap being hung therein without 20 creasing or folding.

Another object of the invention is to provide a receptacle of the above class which is utilized to support the chair, the seat of 25 the chair being of the hinged variety which is adapted to be swung down upon the top of the receptacle and form a closure for this end.

A further object of the invention is the provision of a receptacle for the reception 30 of wraps or the like which is provided with an adjustable bottom, this bottom being capable of being secured in an adjusted position so that the depth of the receptacle may be regulated to adapt it for the reception of 35 long coats or cloaks, or the bottom may be raised to a position toward the seat where it will conveniently receive overshoes, packages or the like.

With these and other objects in view the 40 invention consists of the following novel combination and arrangement of parts, hereinafter more fully described, illustrated in the accompanying drawings and pointed out in the appended claims.

45 In the drawings:—

Figure 1 is a central vertical sectional view of the invention the chair seat being shown swung to an open position by dotted lines;

50 Fig. 2 is a similar view taken at right angles to Fig. 1;

Fig. 3 is a plan view with the seat raised.

Fig. 4 is a transverse sectional view on the line 4—4 of Fig. 1; and

55 Fig. 5 is a sectional view on the line 5—5 of Fig. 4.

Referring to the drawings in detail the numeral 10 designates a floor or other support, which may represent the floor of a theater or other public place. The chair may 60 be of any preferred construction, which includes a back 11 and a hinged seat 12, which may or may not be provided with spring actuated means for normally retaining the same in its raised position, as is usually the 65 case in seats of this construction.

Formed in the floor 10 directly beneath the seat is an opening 13, within which is located the closet or casing adapted to receive the wraps of the occupants of the seat. 70 This casing is vertically disposed beneath the seat and is adapted to support the chair, the said casing extending above the floor 10 to a convenient height for this purpose. The casing also extends beneath the floor a sufficient 75 depth to accommodate wraps such as long coats or opera capes and the like.

The casing is preferably rectangular in cross section and includes the back wall 14, the opposite side walls 15 and the front wall 80 16. The front wall 16 is formed with an opening 17 which preferably extends from the floor to the top of the casing in order to provide convenient access to the interior thereof, it being sometimes desirable to 85 reach within the casing below the depth provided for by the open top thereof, which is closed by the seat 12. If desired this opening 17 may be provided with a suitable door to close the same, this however, is not 90 thought necessary. The casing is secured to the floor 10 by means of the L-shaped corner plates 18, which engage the front, rear and sides of the casing and are secured to the floor around the opening 13, thus utilizing 95 the casing as a support for the chair.

The casing is provided with an adjustable bottom 19, which is preferably of box like construction and is adapted to slidably fit within the walls of the casing, so as to raise 100 and lower therein as desired. In order to adjust the bottom 19, it is provided with hoisting cables 20, which are secured at each side thereof and extend upwardly and pass over pulleys 21 and 22 mounted upon each 105 of the side walls 15 of the casing. The pulleys 22 are located in juxtaposition to the rear wall 14, so that the cables 20 may be secured to the oppositely disposed arms 23 carried by a counterbalance weight 24, which 110 operates in a slot 25 formed in the back of the casing.

For the purpose of securing the bottom 19 in an adjusted position, there are provided the pivoted supporting members 26, these members being mounted in recesses 27 formed in the side walls 15 of the casing, so that they may be swung into these recesses to permit the passage of the adjustable bottom. When it is desired to support the bottom, the supporting members 26 are 10 swung outwardly to permit said bottom to rest thereon, the recesses 27 being provided with a shoulder 28 against which the supporting members rest to prevent their downward movement. Located behind the members 26 are springs 29, which engage said members and act to hold them in either an open or a closed position.

In order to provide for the operation of the lower set of members 26, there is pivotally connected thereto an arm 26^a, which has at its opposite end pivotally connected to a vertical movable rod 26^b, the said rod operating in a groove 26^c in the side walls 15. The upper end of the rod 26^b is formed with 25 a loop or ring 26^d, for convenience of operation.

By reference to Fig. 5 of the drawings it will be seen that by manipulating the rod 26^b the lower set of supporting members 30 may be adjusted so as to permit the bottom 19 to rest thereon, or they may be moved into their seats within the recesses 27, to allow for the passage of the bottom.

Secured to the rear wall 14 of the casing are hooks 30 to conveniently support coats, hats or other garments.

When it is desired to use the receptacle for long coats, cloaks or the like, the seat 12 may be raised and the garments supported 40 upon the hooks 30, the bottom 19 first being lowered to permit the hanging of the garments without having them rest thereon. If desired to place a hat, overshoes, or bundles within the receptacle, the bottom 19 45 may be raised and held in such position by means of the pivoted supporting members 26, so as to keep it within convenient reach.

The hooks 30 are pivoted so as to permit of their being swung horizontally against 50 the wall 14 of the casing, so as to provide additional room for the insertion or removal of the contents of the casing.

It is believed from the foregoing descrip-

tion when taken in connection with the accompanying drawings that the construction 55 and advantages of the invention will be apparent.

The right is reserved to make such changes in the form and proportion thereof as will properly fall within the scope of the 60 appended claims.

Having described the invention, what is claimed, is:—

1. The combination with a chair having a hinged seat, of a vertically disposed 65 casing open at its top and adapted to be closed by said seat and an adjustable bottom for said casing.

2. The combination with a chair having a hinged seat, of a vertically disposed 70 casing supporting said chair, said casing being open at its top and adapted to be closed by said seat and an adjustable bottom for said casing.

3. The combination with a chair having 75 a hinged seat, of a vertically disposed casing supporting said chair, said casing being open at its top and adapted to be closed by said seat, an adjustable bottom for said casing and means for securing said 80 bottom in an adjusted position.

4. The combination with a chair having a hinged seat, of a vertically disposed 85 casing located beneath and supporting said chair, an adjustable bottom for said casing and spring pressed pivoted supports carried by said casing and adapted to be swung into the path of said bottom to support the same.

5. The combination with a chair having 90 a hinged seat, of a vertically disposed casing located beneath and supporting said chair, an adjustable bottom for said casing, cables connected to said bottom and a counterbalance weight carried by said casing.

6. The combination with a chair having 95 a hinged seat, adapted to be positioned over an opening in a floor or other support, of a vertically disposed casing forming a support for said chair and extending through said opening, an adjustable bottom 100 for said casing and means for securing said bottom in an adjusted position.

In testimony whereof I affix my signature.

CHRISTOPHER CHARLES LINDBERG.
